JAMES McPHERSON, OF BROOKLYN, NEW YORK.

Letters Patent No. 79,875, dated June 30, 1868.

IMPROVEMENT IN STEAM-ENGINE CUT-OFFS.

The Schedule referred to in these Letters Patent and making part of the same.

TO ALL WHOM IT MAY CONCERN:

Be it known that I, JAMES McPHERSON, of Brooklyn, in the county of Kings, and State of New York, have invented a new and improved Variable Cut-Off for Steam-Engines; and I do hereby declare that the following is a full, clear, and exact description thereof, which will enable others skilled in the art to make and use the same, reference being had to the accompanying drawings forming part of this specification.

Figure 1 represents a side elevation of a steam-chest, provided with my improved variable cut-off.

Figure 2 is plan or top view, partly in section, of the same.

Figure 3 is a vertical transverse section of the same, taken on the plane of the line $z z$, fig. 1.

Figure 4 is an inverted plan view, showing the connection between the governor and eccentric-spindle which regulate the motions of the cut-off slides.

Similar letters of reference indicate corresponding parts.

This invention relates to a new variable cut-off for steam-engines, which is connected with the governor, so that it will be automatically adjusted as the pressure of the steam comes above or below a certain desired degree.

The invention consists chiefly in the rotating spindles, which are set eccentric in wheels or disks, by which they are carried around, and which have projecting pins, by which they are connected with the cut-off, to which they impart reciprocating sliding motion. The said spindles are also connected with the governor in such a manner that as the balls are more or less spread, the spindles will be turned in the disks, so as to bring their connection with the cut-off nearer to or further from the centre of the rotating disk, and to consequently lengthen or shorten the lever by which the cut off is moved; thereby the cut-off will be caused to move less when the balls are spread than it does when they are closed, and consequently less steam is let into the cylinder when the engine moves fast than there is when it moves slow.

The invention also consists in a device for producing a quick return motion of the cut-off slides, which is produced by a novel device for connecting the eccentric-spindles with the disks that drive them.

A, in the drawing, represents a steam-cylinder, of ordinary or suitable construction.

B and C are the slide-valves, which receive their reciprocating motion from the eccentric on the crank-shaft.

D E are the cut-off slides, moving respectively on the faces of the valves B C.

Each slide or cut-off valve is attached to a horizontal bar, a, which has a slotted arm, b, as shown in fig. 4, the direction of the slot being at right angles to that of the motion of the valve.

F F are two toothed wheels, of equal diameters, mounted on hollow vertical axles that have their bearings in a projecting portion, G, of the bed of the cylinder, or in some other stationary device. These two wheels F mesh into each other, as shown, and receive rotary motion by means of a pinion, c, that is mounted on the governor-shaft H. The governor is of suitable construction and arrangement, and its shaft H receives rotary motion by means of gearing d or otherwise from the crank-shaft.

Through the hollow axle of each wheel F is fitted a circular block or tube, e, as in fig. 3. The lower end or any portion of each block or tube e carries a segmental or other toothed wheel, m, as in fig. 4, both these segments meshing into a toothed bar, g, which is, by a bell-crank, h, connected with a rod, i, that is moved up and down as the sleeve I of the governor moves up and down, the rod i being connected with the sleeve I, as is indicated in fig. 1.

Thus, as the balls J of the governor are spread by rapid motion, the sleeve will be raised, and the bar g will be pushed forward, so as to turn the tubes e in the direction of the arrow 1, fig. 2.

When the balls of the governor drop by slow motion, they lower the sleeve, and thereby the bar g is drawn back to turn the blocks e in the direction opposite to that indicated by the arrows 1.

Upon each tube or block e is placed a plate, or, as I rather term it, spindle, j, which is, by means of a pin, K, connected eccentrically with the tube e, and which is, by means of a pin, f, that projects from the wheel F, connected also with the said wheel F. From the face of each spindle j projects an eccentric-pin, l, through one of the slotted arms, b, as shown.

By the rotating wheel F, the spindle *j*, connected with each wheel, is revolved around the eccentric-axle K; and, as the spindle is thus revolved, it will impart, by its connection *l b a*, reciprocating motion to the cut-off valve to which it belongs. As the spindle is carried around the axis K, which is eccentric to the shaft around which the pin *f* driving the spindle turns, it follows that the spindle will turn quicker when the pin *f* is nearest to the axis of the spindle, and slower when they are further apart. Now, the pin *l* is so set on the spindle, that it serves to close the slide D or E, when the said pins *f* and K are nearest together; and thus a quick return motion of the cut off is obtained.

By the aforementioned adjustment of the tubes *e* by the governor, the axis of the spindle is by the governor turned, so as to set the pin *l*, on the spindle, nearer to or further from the axis of its wheel F, and the lever acting upon and moving the cut-off valves, will consequently be lengthened or shortened by such an adjustment of the pin *l* towards the axis of the wheels.

Thus, when the governor-balls are quite extended, the pin *l* of the spindle and the axis of the wheel will be near together, so that but very little motion is imparted to the cut-off valve, which will then not far open the aperture of its slide-valve.

If the pin *l* were brought quite in line with the axis of the wheel, the cut-off would not be moved at all. When the pin *l* is, by the slow motion of the governor, brought further off the axis of the wheel F, the lever operating on the cut-off will be lengthened, and the motion of the cut-off increased, so as to let a larger quantity of steam into the cylinder.

The pin *f*, which divides the spindle, must, to allow the aforesaid adjustments of the spindle, fit through a slot in the spindle, as shown.

I claim as new, and desire to secure by Letters Patent—

1. The arrangement and combination, with each other, of the rotating wheels F, (fitted around the tubes or loose axles *e*), and of the spindles *j*, connected eccentrically with the axles *e*, and also with the wheels F, and with the cut-off slides D and E, substantially as herein shown and described.

2. The movable sleeve I of the governor, levers *i h*, and rack *g*, with the tubes or axles *e e*, arranged substantially as herein shown and described, whereby to vary the cut-off with the motion of the engine, as set forth.

3. The construction and arrangement of the eccentric-spindle *j*, whereby to convert the rotary motion of the wheel F into the reciprocating motion of the cut-off, and which is adjustable in and by the axle *e* of the wheel F, that turns loose in the wheel, as set forth.
